UNITED STATES PATENT OFFICE

ELIAS ZIEGLER, OF NEW YORK, N. Y.

DESIGN FOR A COMBINATION TRAY AND LAMP STANDARD

Application filed April 1, 1932. Serial No. 43,356. Term of patent 7 years.

To all whom it may concern:

Be it known that I, ELIAS ZIEGLER, a citizen of the United States, residing at 225 West End Avenue, New York city, in the county of New York and State of New York have invented a new, original, and ornamental Design for Combination Tray and Lamp Standard, of which the following is a specification reference being had to the accompanying drawing, forming part thereof.

Figure 1 is a side elevation of the complete design.

Figure 2 is a plan view of the tray portion of the device which embodies the dominant portion of the design.

Figure 3 is a front elevation of the tray portion shown in Figure 2.

I claim:

The ornamental design for a combination tray and lamp standard substantially as shown and described.

ELIAS ZIEGLER.
